UNITED STATES PATENT OFFICE.

ELMER H. SMITH, OF MINNEAPOLIS, MINNESOTA.

PROCESS OF MAKING OXYFUEL TORCH TIPS.

Application filed March 18, 1926. Serial No. 95,605.

This invention relates to the oxy-fuel torch tip invention shown and described in my pending application for Letters Patent of the United States #82,044, filed January 18, 1926, and the object of my present invention is to provide a means whereby the gases flowing through the passages or ducts in the tip will be mixed thoroughly before reaching the exit orifice of the tip, the structure of the tip and the method of forming the longitudinal gas passages or ducts therein being substantially the same as described in my application above referred to.

The invention consists generally in various constructions and combinations all as hereinafter described and particularly pointed out in the claims.

In the accompanying drawings forming part of this specification,

20 Figure 1 is a view of a core having a tapered end ready to receive the longitudinal groove or ducts therein;

25 Figure 2 is a view partially in section showing the completed ducts with annular grooves formed in the surface of the core and intersecting the longitudinal ducts or gas passages;

30 Figure 3 is a sectional view on the line 3—3 of Figure 2;

35 Figure 4 is a sectional view on the line 4—4 of Figure 2;

Figure 5 is a longitudinal sectional view showing the tip completed and ready for use with the central bore therein and the longitudinal ducts and the encircling jacket or shell formed by immersing the core in an electro-plating bath;

40 Figure 6 is a view corresponding to Figure 2 showing a modified means for connecting the longitudinal grooves or passages to insure the mixing of the gases before delivery to the end of the tip;

Figure 7 is a transverse sectional view on the line 7—7 of Figure 5.

45 In the drawing, 2 represents a core of suitable material having a tapered end 3 and provided with a longitudinally arranged central bore 4. The core may be of a suitable gauge of tubing with the bore centrally formed therein and provided with comparatively thick heavy walls in which a series of gas ducts are usually formed by drilling as fully described in my application above referred to. This drilling operation has 55 been found to be both laborious and ex-

pensive and as fully described in my pending application, I will or otherwise form a series of longitudinal grooves or ducts 5 suitably spaced apart in the surface of the core 2 and running from end to end thereof. In 60 this particular tip as illustrated in Figure 3, I have shown six of these grooves or ducts, but do not confine myself to this number as any other suitable number may be provided depending upon the size of the tip and the 65 purpose for which it is to be used.

Within these grooves, I place strips of fusible material 6 and then I immerse the core in an electro-plating bath and let it remain therein until a sufficient quantity of 70 metal has collected over the outer surface of the tip and over the ducts and the strips of fusible metal therein to form a shell or jacket of suitable thickness. The end of this shell or jacket will then be machined in a suitable 75 manner to form the discharge orifice of the tip and the jacket is exteriorly threaded as at 7 and provided with a collar 8, by means of which the tip may be inserted into the head of the torch or as shown and described in 80 detail in my application above referred to. The fusible strips 6 when subjected to heat, can be readily discharged from the grooves, leaving them clear and unobstructed for the 85 flow of gas through the tip. The shell or jacket is provided at intervals with ports 9 leading to the longitudinal ducts, and to effect a thorough mixture of the gases it is desirable to have these longitudinal ducts communicate with each other intermediate to 90 the ends of the tip. I, therefore, provide annular grooves or recesses 10 in the surface of the core adapted to communicate with each of the longitudinal ducts and allow the 95 gases therein to flow around the core and the gas in one longitudinal duct to mix and mingle with the gases of all the other corresponding ducts before reaching the end of the tip. These annular grooves 10 after being formed 100 in the peripheral surface of the core are filled with a suitable fusible material 6^a corresponding to that described with reference to the longitudinal ducts. This fusible material will be melted and discharged from the grooves at the same time that the ducts 105 are cleared of the fillers therein by the application of heat thereto.

When these longitudinal ducts and the annular grooves have all been cleared of the 110 fusible material therein, the ducts will be

- unobstructed to the flow of gas therethrough and the annular grooves will insure the distribution of the gases around the peripheral surface of the core and the proper and uniform mingling of the gases in each duct with the gases of all the other ducts. Then when the unfinished outer surface of the shell or jacket has been suitably machined, the tip is ready for mounting in the head of the
- 10 torch and all the labor incidental to the drilling of the tip has been eliminated as well as the expense caused by the time required for such drilling and the almost continual breakage of drills and discarding of
- 15 the partly or nearly finished tips.
- In Figure 6, a modified construction is shown which consists in providing a spiral groove 10 in the surface of the core extending at an incline in the surface instead of in
- 20 a direct line transversely of the axis of the core, this spiral groove having all the functions of the grooves 10 and insuring the thorough mixture of the gases flowing longitudinally through the ducts. The tapered
- 25 end of the core serves to converge the ends of the ducts and deliver the gases at a single point. I have shown this core equipped with a central bore but it will be understood that it may be formed into a tip as shown in Figures
- 30 9 to 15 of my application above referred to in which the peripheral surface of the core has longitudinal grooves or ducts therein, but the central bore is omitted entirely, and except for the annular or spiral recess or grooves extending circumferentially of the core the device shown herein corresponds in construction and method of manufacture to that of my application above indicated. When the jacket of the desired
- 40 thickness has been formed around the core, the fusible material, wax or whatever substance may be placed in the ducts and grooves, will be fused and discharged and then when the tip has been suitably machined, it is ready for mounting in the torch head and for use.

I claim as my invention:

1. A process of making a one-piece oxy-fuel gas tip which consists in providing a core, forming a series of longitudinal and transverse grooves in the peripheral surface of the core, filling these grooves with a material fusible at low temperature, immersing the core in an electro-plating bath until a shell or jacket of the desired thickness has been formed over and around the longitudinal and transverse grooves, then fusing the material in said grooves, thereby forming a series of longitudinal and transverse gas ducts in the tip.
2. A process of making a one-piece oxy-fuel gas tip which consists in providing a core having a tapered end forming a series of longitudinal grooves in the peripheral surface of the core, converging toward each

other in said tapered end and also forming a transverse peripheral groove intersecting said longitudinal groove, immersing the core in an electro-plating bath until a shell or jacket of the desired thickness has been 70 formed over and around said grooves to thereby provide a series of longitudinal ducts through the tip, and a peripheral mixing groove intersecting said ducts.

3. A process of making an oxy-fuel gas 75 tip which consists in providing a core, grooving or milling the peripheral surface of the core to form a series of longitudinal recesses, forming a peripheral groove intersecting said longitudinal recesses to form a 80 communicating passage between them, filling these grooves and recesses with a substance fusible at a comparatively low temperature, immersing the core in an electro-plating bath until a shell or jacket of the 85 desired thickness has been formed thereover and then fusing the material in said recesses and grooves to provide a series of longitudinal ducts therein, and an intersecting transverse recess or duct communicating 90 with said longitudinal ducts.

4. A process of making an oxy-fuel gas tip, which consists in providing a core, grooving or milling the peripheral surface thereof to provide a series of surface recesses 95 therein, filling these recesses with a substance fusible at a comparatively low temperature, immersing the core in an electro-plating bath until a shell or jacket of the desired thickness has been formed thereover and 100 then fusing the material in said recesses to provide a series of longitudinal ducts therein.

5. A process of making an oxy-fuel gas tip which consists in providing a core having a 105 tapered end, grooving or milling the peripheral surface of the core to form a series of longitudinal recesses converging at one end of the core, filling these recesses with a substance fusible at a comparatively low 110 temperature, immersing the core in an electro-plating bath until a shell or jacket of the desired thickness has been formed over the core and grooves, and then fusing the material in the grooves to provide a series 115 of longitudinal ducts therein.

6. A process of making an oxy-fuel gas tip which consists in providing a core and forming a longitudinal bore centrally therein, grooving or milling the peripheral surface of the core to provide a series of surface recesses therein, filling these recesses with a substance fusible at a comparatively low temperature, immersing the core in an electro-plating bath until the shell or jacket 120 of the desired thickness has been formed over the core and grooves and then fusing the material in the grooves to provide a series of longitudinal ducts therein.

7. A process of making an oxy-fuel gas 125

tip which consists in taking an elongated block of metal forming a core, boring it centrally and longitudinally, tapering one end of the core and forming at intervals in its peripheral surface a series of longitudinal ducts or recesses, filling these recesses with a material fusible at a comparatively low

temperature, placing the core in an electro-plating bath to form a jacket or shell encircling the core over said recesses and then ¹⁰ fusing the material in said recesses.

In witness whereof, I have hereunto set my hand this 15th day of March, 1926.

ELMER H. SMITH.
